United States Patent Office.

ARCHIBALD WILLISCROFT, OF WILMINGTON, DELAWARE.

Letters Patent No. 94,369, dated August 31, 1869.

IMPROVEMENT IN HOSE-PIPE NOZZLES.

The Schedule referred to in these Letters Patent and making part of the same.

To all whom it may concern:

Be it known that I, ARCHIBALD WILLISCROFT, of Wilmington, in the county of Newcastle, and State of Delaware, have invented a new and useful Improvement in Hose-Pipe Nozzles; and I do hereby declare that the following is a full, clear, and exact description thereof, which will enable others skilled in the art to make and use the same, reference being had to the accompanying drawings, forming part of this specification, in which—

Figure 1 is a longitudinal section of my improved hose-pipe nozzle, taken through the line $x\ x$, fig. 2.

Figure 2 is a cross-section of the same, taken through the line $x\ x$, fig. 1.

Similar letters of reference indicate corresponding parts.

My invention has for its object to furnish an improved nozzle for hose-pipes, which shall be so constructed and arranged that it may be easily and quickly adjusted to throw a larger or smaller stream of water, as may be desired; and

It consists in the construction and combination of various parts of the nozzle, as hereinafter more fully described.

A represents the nozzle-pipe, which is screwed to the hose-pipe in the ordinary manner.

B is a ring-plate, secured by screws to the end of the nozzle-pipe A.

The ring-plate B and nozzle-pipe A, either or both, have shoulders formed upon them, so as to form a slot between them, for the reception of plate C.

The plate C has two or more holes, of different sizes, formed through it, so that by adjusting its position, a larger or smaller stream of water may be thrown, as may be desired.

The plate C may have flanges formed upon its ends,

to prevent its being accidentally drawn wholly out of its slot.

D is a pin, passing through a hole in the flange of the pipe or nozzle A, and which, when the plate C is adjusted in place, enters a hole or recess in the plate C, and holds it securely in place while the nozzle is being used.

The pin D is held forward by a small spring, E, coiled around it, as shown in fig. 1.

Upon the outer end of the pin D is formed, or to it is attached, a small arm or thumb-piece, F; and upon the pipe A, at the side of the pin D, is formed, or to it is attached, a small inclined projection, G, so that by turning the thumb-piece F against the inclined projection G, the pin D will be withdrawn from the plate C and held away, allowing the said sliding plate C to be conveniently adjusted, as required.

Having thus described my invention,

I claim as new, and desire to secure by Letters Patent—

1. The combination of the sliding-plate C, having two or more different sized holes formed through it, and the ring-plate B, with each other and the nozzle-pipe A, substantially as herein shown and described, and for the purpose set forth.

2. The pin D, provided with the spring E and thumb-piece F, when constructed and arranged with reference to the inclined projection G and sliding plate C, as herein shown and described, for the purpose specified.

The above specification of my invention signed by me, this 27th day of April, 1869.

ARCHIBALD WILLISCROFT.
